UNITED STATES PATENT OFFICE.

OLIVER E. BENNETT, OF NEW YORK, N. Y.

DESIGN FOR A COMBINED BOTTLE-OPENER AND DOOR-LOCK.

59,403.

Specification for Design.

Patented Oct. 18, 1921.

Application filed February 23, 1921. Serial No. 447,330. Term of patent 14 years.

To all whom it may concern:

Be it known that I, OLIVER E. BENNETT, a citizen of the United States, residing at New York, in the county of New York and State of New York, have invented a new, original, and ornamental Design for a Combined Bottle-Opener and Door-Lock, of which the following is a specification, reference being had to the accompanying drawing, forming a part thereof.

In the accompanying drawings:

Figure 1 is a face view of a combined bottle opener and door lock.

Fig. 2 is an edge view thereof.

I claim—

The ornamental design for a combined bottle opener and door lock, as shown.

OLIVER E. BENNETT.
